(57) **CLAIM**

The ornamental design for a gas leak detector, as shown and described.

DESCRIPTION

1.-2. Gas leak detector

1.1 is a perspective view.

1.2 is a front view.

1.3 is a rear view.

1.4 is a right side view.

1.5 is a left side view.

1.6 is a top view.

1.7 is a bottom view.

2.1 is a perspective view.

2.2 is a front view.

2.3 is a rear view.

2.4 is a right side view.

2.5 is a left side view.

2.6 is a top view.

2.7 is a bottom view.
